TOY PARACHUTE AND PROJECTOR
THEREFOR

Eugene L. Orr, Orlando, Fla.

Application September 4, 1946, Serial No. 694,808

1 Claim. (Cl. 46—86)

1

This invention has to do with aerial toys. It is of that type designed to be thrown into the air in upward flight. It may be projected in upward flight in any suitable manner, as for example, and as here shown by a catapult. It has for its object the provision of a projectile toy of this type in which, after its initial upward flight, the toy will reverse and go into a flight under the influence of gravity, and upon such reversal a collapsed parachute forming part of the toy, will be released and permitted to expand, whereupon the toy will parachute slowly to the ground.

In the embodiment here shown this result is accomplished by providing a hollow casing in which a collapsed parachute is initially stored for the upward flight; means for automatically ejecting the parachute on reverse or downward flight of the toy; means, operable when the toy starts its downward falling flight, to trip and release the ejecting means to permit it to expel the parachute from the casing; allow it to open, and float the toy to the ground.

In the drawings herewith one physical embodiment of the invention is shown.

In said drawings:

Figure 1 is a view in side elevation of a toy ready for launching.

Figure 2 is a view in side elevation of a catapult useful for launching the toy, the elastic strip being broken away for compactness of illustration.

Figure 3 is a sectional view of the casing of the toy showing the parts housed therein taken on line 3—3 of Figure 1.

Figure 4 is a view in side elevation showing the toy reversed with the parachute open ready for descent.

Figure 5 is a sectional view through the casing in reverse position to that shown in Figure 3 with the spring expanded.

Figure 6 is a view in side elevation of a portion of the casing and one of the wings.

Figure 7 is a view to show the manner of launching the toy.

Referring to the drawings by numbers, the same numbers designating the same parts in the several views, a hollow casing 10 of any suitable length is provided with a closed end 11, which is the contact end when the toy reverses after launching and falls in downward flight. The casing 10 is preferably round in cross section, although it may take other forms, and has near its end 11 a fixed disk 12. Projecting through the side of the casing 10 and prefer-

ably anchored in disk 12, is a projection 13 to which the end of a launching means, such as an elastic catapult strip 14, when a catapult is used, may be connected with a freely detachable coupling, as, for example, a ring 15. Catapult 14 will be positioned as shown in Figures 2, 3, and 7, and the operator, holding the catapult handle 16 in one hand and the toy casing 10 in the other, will tension catapult 14 and launch 10 the toy, the catapult coupling being instantly disengaged. Catapult 14, here shown as a strip of elastic, may be secured in any suitable manner to the handle 16 and to the cord 15' connected with the ring 15. As here shown conventionally, clamps 14' are provided which may be readily disconnected for renewal or replacement of the parts.

Anchored at one end in any suitable manner to the fixed disk 12 is a spring 17. The other 20 end of spring 17 is fastened to a movable disk 18 provided with parachute holding means, as, for example, eye 19, to which the shrouds 20 of a parachute 21 are attached. Parachute 21 is stored initially in collapsed condition in the 25 open-ended casing 10, with the spring 17 compressed between the fixed disks 12 and the movable disk 18, as shown in Figure 3. Disk 18 is held in spring compressing position by means of a flexible connection 22, one end of which passes 30 through a hole in the casing 10 and is secured to disk 18, the other end of flexible connection 22 being coupled to a latch 23 pivoted at 24 to the casing 10. The free end of latch 23 is engaged with a trip, here shown as a loop 25 35 pivotally mounted on casing 10. In these positions of the parts, the toy is ready for launching, the spring 17 being under compression and held by the latch 23 and trip 25, with the parachute 21 stored in collapsed condition in the open-ended casing 10.

Secured to the casing 10 in any suitable manner, as, for example, by means of the frame 26 having laterally projecting portions 27, are pivotally mounted wings 28, two being here shown, 45 although more than two wings may be provided, if desired. Wings 28 are connected by elastic pulls 29, rubber cords being one useful form of connection, running from eyes 30 on the wings, through laterally extending projections 31 on the wings, to fixed eyes 32 on the casing 10. The elastic connections 29 tend always to elevate the wings to their open or extended positions, as shown in Figure 4, but when the toy is launched on its initial upward flight, air pressure on the wings will hold them, against the pull of the 50 55

elastic connections 29, in the positions shown in Figure 1, parallel to the casing 10. When the toy reverses for its downward flight (see Figure 4) air pressure on the wings will be reversed, and, under such pressure and the pull of the elastic connections 29, the wings will open and maintain that position during descent of the toy.

In order to release the parachute 21 from its collapsed and stored position in casing 10, the trip 25, which holds latch 23 of the spring holding cord 22, is connected by pull cords 33 running through an eye 34 on casing 10, to the ends of wings 28 at 35. When the wings 28 swing to open position in the descent of the toy, the cords 33 pull the trip 25, releasing latch 23, cord 22, and disk 18. This releases spring 17, which moves disk 18 to the position shown in Figure 5, and ejects the parachute 21, which then opens and floats the toy to the ground. It will be seen that the toy is in reverse downward flight before the wings open and release the parachute ejecting means, so that the position of the toy is such that the parachute is thrown clear of the toy and danger of entanglement with any part of the toy is eliminated. Following the construction here shown and described, an aerial toy having novel and interesting features can be developed; one which is easily manufactured; which can be made at reasonable cost, and which will stand up under continued use.

A particular construction is disclosed. Mechanical variations of the structure may be made. All such variations as are comprehended by the appended claims, are to be regarded as within the purview of the invention.

I claim:

A toy of the class described comprising a hollow casing having a closed end and an open end, a collapsed parachute in said casing, said casing having a spring anchored at one end thereof, a spring compressing disk axially movable in said casing and coupling the other end of said spring

and said parachute, a flexible member connected to said disk to move the same and compress said spring, said flexible member extending exteriorly of said casing, a latch to lock said flexible member and disk in spring compressing position, a trip to hold said latch in locking position, spaced wings, means pivotally connecting said wings to the outer side of said casing, said wings being normally maintained in a collapsed position substantially parallel with the casing, elastic means connecting the wings intermediate their ends to the closed end of the casing and normally urging the wings to be moved about their pivots to their opened position, the pressure of the air against the wings when the toy is launched on its initial upward flight maintaining the wings substantially parallel against the pull of the elastic means and when the toy reverses its direction in its downward flight, the air pressure on the wings decreasing sufficiently to cause the wings to open, and means operatively connecting the wings to said latch so as to eject the parachute from the casing and automatically open the parachute in the downward flight of the toy.
